UNITED STATES PATENT OFFICE.

HOWARD S. HART, OF NEW BRITAIN, CONNECTICUT, ASSIGNOR TO THE HART & COOLEY COMPANY, INCORPORATED, OF NEW BRITAIN, CONNECTICUT, A CORPORATION OF CONNECTICUT.

REGISTER AND VENTILATOR.

Application filed January 10, 1922. Serial No. 528,346.

To all whom it may concern:

Be it known that I, HOWARD S. HART, a citizen of the United States of America, residing at New Britain, Conn., have invented 5 a new and useful Register and Ventilator, of which the following is a specification.

My invention relates to certain new and useful improvements in ventilators for the distribution of hot or cold air, and the same 10 is particularly useful when employed in the side wall of a room or compartment. One object of the invention is to provide a construction which will offer a minimum of resistance to the free flow of air therethrough 15 from the air supply pipe with which the ventilator is associated. Another object is to improve the means for supporting and adjusting the valve so-called. Other objects will appear to the mechanic skilled in the art 20 from a reading of the accompanying specification and an examination of the accompanying drawings, in which,

Fig. 1 is a front elevation.

Fig. 2 is a rear elevation of the parts 25 shown in Fig. 1.

Fig. 3 is a cross-section on the line 3—3 of Fig. 1.

Fig. 4 is a relatively enlarged cross-section on substantially the plane of line 4—4 of 30 Fig. 1.

Fig. 5 is a relatively enlarged perspective of certain details.

In the particular form shown, I shall describe my invention as applied to what is 35 termed a side-wall ventilator or register of the type designed to be located on the side wall of a room next to the floor.

In the drawings 1 is a casing, the front of 40 which is preferably tilted back slightly in some cases, although not always. The central portion of the casing is open and is provided with a removable front plate of rectangular outline. This front plate comprises the side border strips 2—2 connected to top 45 and bottom border strips 3—4 respectively. The top and bottom border strips 3—4 are provided with rearwardly extending flanges 5—6. Arranged vertically and secured to 50 said flanges 5—6 are thin bars 7—7 which are placed edgewise to the direction of the flow of air through the ventilator. As shown these bars are several times greater in depth than in thickness so as to not only afford the necessary strength but also to partially hide

the air passage excepting when viewed from 55 directly in front. It is manifest that these bars, being of substantial depth and arranged reasonably close together, will offer obstruction to the vision when the register is looked at from one side while at no time 60 will they offer any appreciable resistance to the free flow of air between them. Again such thin bars will not create eddy currents which tend to back up and baffle the passage 65 of air through the ventilator. The lower edge of the border strip 4 may be provided with lugs 4^a—4^a (see Fig. 2) which pass into appropriate slits or openings in the casing 1 when the parts are assembled. The upper border strip 3 may be provided at its back 70 with turn-buttons 8—8 which are arranged in one position to pass through corresponding openings in the casing 1, and each of which may be turned by a handle, such as indicated at 8^a located at the front of the top border strip, so as to lock the front plate to the casing 1 in the position indicated in Fig. 75 4. The flange 5 at the lower edge of the upper border strip 3 is extended back sufficiently far to support a bearing rod or shaft 9 (see Fig. 2), the ends of which may be bent up and secured to the underside of said flange. 10—10^a are gripping plates which embrace said bearing shaft the lower edges 80 of said plates being preferably secured as by a rivet 11, to a valve plate 12. The area of the valve plate is sufficient to close the passage through the ventilator when said plate 12 is moved into the position shown in solid lines in Fig. 3. 14 is a screw by which an operating handle 15 may be secured to the front 85 of the valve plate 12. This screw passes freely through the plate 10^a and screws into the plate 10 as best seen in Fig. 4. By turning the screw 14 the plates 10—10^a will be caused 90 to pinch on the bearing 9 with the desired degree of friction to hold the valve 12 in any desired position of adjustment. The handle 15 is suitably shaped to pass through between two of the bars 7, and project sufficiently far beyond the front to be easily 95 accessible for valve operation. The various pieces may be secured together in any desired way, but the bars 7 are preferably reduced slightly at their ends, the reduced portions being riveted to the flanges on the upper and lower border strips 3—4 respectively. By this means mutual support is 100 105

afforded and accidental displacement of the bars will be avoided. The bars 7 are preferably stamped out of sheet metal. It will be understood that I have shown the invention 5 in its preferred form.

The valve is preferably a one-piece plate pivoted at its edge to swing, and the hinge pin or shaft is transverse to the direction of the cross bars so that the valve will perform 10 the double function of a valve and a deflector.

What I claim is:

In a face plate for ventilators and the like, 15 a rectangular frame composed of top, bottom, and side border strips connected together, rearwardly directed flanges on the top and bottom strips, a plurality of thin cross bars, each bar being connected at its ends to said rearwardly directed flanges, said

bars being arranged side by side and edge-wise with relation to the front of the plate to form free ventilating passages, a shaft bearing secured to the upper flange and positioned at the rear of said cross bars, a plate valve and a connection between said plate valve and said shaft bearing comprising jaws which embraces said shaft bearing, with means for operating said jaws to vary the effective frictional tension of the same on said bearing, with a handle secured to 30 said plate valve projecting forwardly between two of said cross bars for manual operation at the front of said plate, said jaw operating means serving also as the sole means of attachment of said handle to said 35 valve plate.

HOWARD S. HART.
